UNITED STATES PATENT OFFICE.

ARTHUR L. HALLIDAY, OF YONKERS, NEW YORK, ASSIGNOR TO THE
BIGELOW CARPET COMPANY, OF CLINTON, MASSACHUSETTS.

DESIGN FOR A CARPET.

SPECIFICATION forming part of Design No. 13,252, dated August 22, 1882.

Application filed July 28, 1882. Term of patent 3½ years.

To all whom it may concern:

Be it known that I, ARTHUR L. HALLIDAY, of Yonkers, in the county of Westchester and State of New York, have invented a new and original Design for Carpets, of which the following is a specification.

This invention relates to a new and original design for carpets and similar fabrics; and it consists in the novel grouping and configuration of parts hereinafter more fully described.

The accompanying photograph illustrates a face view of a carpet having my new design.

A is a band ornamented along its top with a series of vertical lines, below which runs a series of fine dots, and below these extends a row of hanging figures somewhat resembling the pendulum of an ordinary clock.

Below the band A extends the band B, containing ornamentation composed of leaf-like figures somewhat in the shape of a capital X set at intervals, and having set between them flower-like figures bearing umbrella-shaped blossoms on slender stems. The stripe B is separated from the stripe D by the band b, containing an ornamentation of small figures, each apparently divided into four quarters.

The stripe D has an ornamental background composed of dots, crosses, rectangles, small circles, and other figures set together in various shapes, and on this background appears the figure d, resembling an open rose set upon a leafy stem, and also the figure e, resembling

a full-blown rose with its accompanying leaves and sprays apparently hanging over into the stripe E.

35

The stripe E has an ornamentation resembling rows of many-pointed stars running across it, each star being separated from the next one by a small rectangle, around which are outlined the rays of another star.

40

The band F contains an ornamentation of vertical lines having a series of dots and circles above it.

I claim—

1. The design for a carpet, consisting of band 45 A, substantially as shown.

2. The design for a carpet, consisting of stripe B, containing figure a, substantially as shown.

3. The design for a carpet, consisting of stripe D, containing figures d and e, substantially as 50 shown.

4. The design for a carpet, consisting of stripe E, substantially as shown.

5. The design for a carpet, consisting of band b, stripe D, containing figures d and e, and 55 stripe E, substantially as shown.

6. The design for a carpet, consisting of band A, stripe B, containing figures a, band b, stripe D, containing figures e and d, stripe E, and stripe F.

ARTHUR L. HALLIDAY.
